UNITED STATES PATENT OFFICE

171,536

PILLOWCASE

Anna Z. Flanagin, Bozeman, Mont.

Application August 13, 1953, Serial No. 26,442

Term of patent 3½ years

(Cl. D92—26)

To all whom it may concern:

Be it known that I, Anna Z. Flanagin, a citizen of the United States of America, residing at Bozeman, in the county of Gallatin and State of Montana, have invented a new, original, and ornamental Design for a Pillowcase, of which the following is a specification, reference being had to the accompanying drawing, forming part thereof.

I claim:

The ornamental design for a pillowcase, as shown.

ANNA Z. FLANAGIN.
